COMFORT STATION

William F. McClenahan, 778 Burlway Road,
Burlingame, Calif.

Filed Feb. 6, 1962, Ser. No. 68,675

Term of patent 14 years

(Cl. D13—1)

FIG. 1.

FIG. 2.

FIG. 3.

FIG. 4.

FIG. 5.

FIG. 6.

FIGURE 1 is a perspective view of the new comfort station embodying my design.

FIGURE 2 is a front elevation of the comfort station.

FIGURE 3 is an end view of the comfort station.

FIGURE 4 is a top view of the comfort station.

FIGURE 5 is a back view of the comfort station.

FIGURE 6 is an end view showing the end opposite that shown in FIGURE 3.

I claim:

The ornamental design for a comfort station, as shown.
